ABSTRACT OF THE DISCLOSURE

A device for the continuous manufacture of artificial sponges obtained by the electrical coagulation of a pulp consisting of viscose, reinforcing fibres and porosity-creating material, said device comprising a horizontal plate, rotatable and capable of receiving or forming an annular mould open at its upper portion, the mould being connected to a source of electric current and passing during its rotation in front of fixed stations comprising a pulp-feeding station, pressing means alternating with means for extracting the liquor exuded during the coagulation of the pulp from said mould, means for re-cycling part of the liquor into the mould, said means being followed by an extraction station at which the pulp arriving in a coagulated state is extracted from the mould by means of driving means external to said plate, a mould-washing station located between the feeding station and the adjacent extraction station being arranged to form a lock-chamber in the mould.

The present invention relates to a device for the continuous manufacture of artificial sponges, especially of regenerated cellulose.

Devices are already known which are arranged for the continuous manufacture of artificial sponges by the coagulation of a pulp composed of viscose, reinforcing fibres, and porous material. Following one method of manufacture, these sponges are produced by means of a device comprising a die with a vertical axis, extended by a sleeve having a section larger than the die, and which is provided with means intended to ensure the coagulation of the pulp. These coagulation means are constituted by electrodes and a large number of parallel fingers which ensure constant contact between the electrodes and the pulp. By this means, the electric current causes an increase in the temperature of the pulp and thus ensures its coagulation.

After the sleeve and beyond the electrodes, the roll of coagulated pulp first passes through a tank containing a bath composed of a solution of sodium sulphate at 90°—100° C., and then through the usual washing and finishing baths, together with a drying apparatus, after which the dry product can be shaped and cut-up.

Following another method which is also known for the continuous manufacture of artificial sponges of regenerated cellulose, the pulp is formed into a roll in a device comprising a channel of insulating material, the walls of which are lined with metal plates and inside which circulates the upper side of an endless conveyor belt or rubber; the coagulation of the pulp, brought-up to a pre-

2

determined point directly above the belt is obtained electrically through the intermediary of moving electrodes arranged along the lateral walls of the channel, these electrodes being in contact with the sides of the mass of pulp in motion.

In a device of this kind, the electrodes are constituted by two series of contiguous metal plates which are fixed on chains with links travelling on the upper edges of the channel, the coagulated roll being then discharged on to a table, beyond the electrodes, and then subjected to the usual finishing and drying means and finally to the shaping process.

In addition to the fact that they are of complicated construction, these devices do not give complete satisfaction, especially since, during its coagulation, the pulp is subjected to displacements and other handling which may lead to deformation and also may result in a finished product having an external appearance which leaves much to be desired.

The present invention has for its object to eliminate the drawbacks mentioned above, and proposes to this end a device which, in addition to a simple construction and robust structure, has numerous advantages.

According to the invention, the device for the continuous manufacture of artificial sponges obtained by coagulation of a pulp composed of viscose, reinforcement fibres and porous material, is especially characterized in that it comprises at least one plate capable of rotation and adapted to receive and/or to form at least one annular mould, open at its upper portion, the said mould being on the one hand coupled to a source of electric current, and on the other hand passing during its rotation in front of fixed stations comprising respectively a pulp-feeding station, pressing means alternating with means for extracting the liquid and means for re-cycling part of this latter into the said mould, which are followed by an extraction station at which the pulp arriving in the coagulated state is extracted from the mould by means of carrying means external to the plate, while a washing station for the said mould is arranged between the feeding station and the neighbouring extraction station, and is adapted to form a lock-chamber in the said mould.

With this arrangement, it can immediately be seen that the use of a rigid rotating mould passing in front of fixed stations permits coagulation of the pulp which is stationary with respect to the mould. For this reason, the risk of deformation is eliminated and therefore the finished product has an outer surface free from irregularities.

Other characteristic features and advantages of the invention will furthermore be brought out in the description which follows below, given by way of example, reference being made to the accompanying drawings, in which:

FIG. 1 is a diagrammatic plan view of the device according to the invention, this device being seen from above.

FIG. 2 shows a perspective view of the feeding station;

FIG. 3 is a similar view, showing a pressing device;

FIG. 4 illustrates, also in perspective, the sprinkling and re-cycling means;

FIG. 5 shows the extraction station for the formed roll from the mould, together with the roll-carrying station;

FIG. 6 illustrates the washing station for the mould.

In the preferred form of construction chosen and shown in FIGS. 1 to 6, the device according to the invention comprises a plate 10 capable of rotation about a vertical axis 0. With the upper surface of this plate is associated an annular mould indicated generally at 11, which is concentric with the axis of rotation. This mould has a U-shaped straight transverse section, and is constituted as shown in FIG. 2 by a base 12 of insulating material fixed to the plate, and by vertical metal walls 13 and 14. Each of the walls is composed of a plurality of elements 15 suitably curved, mounted end-to-end and connected together by means of waterproof and insulating expansion joints 16, the whole assembly thus formed constituting the mould proper 11.

The elements 15 of each of the walls of the mould are connected together electrically by means of two-pole contactors shown diagrammatically at 17 to a transformer 18 fixed for example in a central part of the plate 10 and connected in any suitable manner to a source of electric current which has not been shown.

At the upper portion (see particularly FIGS. 2 to 6), the vertical walls of the mould are provided on their edges with gutters 19 and 20, the purpose of which will be explained later. These gutters, of metal or insulating material, are in communication through the intermediary of tubes 21 with a recovery tank arranged for example underneath the plate 10.

The plate 10 is enclosed externally by a ring 22 which is fixed and on which are mounted the elements belonging to each of the stations arranged immediately above the mould and at pre-determined positions. The position of the pulp-feeding station is shown at 23, while 24 designates the pressing means; the liquid sprinkling means 25 are supplied by the re-cycling means 26, while 27 indicates the extraction station for the bar of material which arrives at this point in a coagulated state, while 28 shows the means for transferring the bar to the finishing baths (not shown). Between this last station and the feed station, there is provided a mould washing station 29.

Each of these units will now be described in greater detail, beginning with the pulp-feeding station, more clearly shown in FIG. 2, from which it can be seen that the pulp P is fed into the mould 11 by means of an endless screw 30 rotating inside a conduit 31 extended by a conduit 32 which is elbowed twice, and the end section 33 of which is preferably shaped in such manner as to have a direction tangential to the interior of the mould at the same time being very close to the insulating base 12 of the mould.

On the other end of the pulp-feeding station the direction of rotation of the plate (arrow F), are arranged pressing means 24a to 24g, the latter being close to the extraction station 27. Each of these pressing devices comprises (see FIG. 3) a roller 36 of insulating material mounted radially above the mould and carried by a cross-arm 35 fixed to the outer ring 22. These rollers rotate freely and can slide in a vertical plane by means of slots 37, so that they remain continuously in contact with the upper surface of the bar of pulp P.

Between the rollers 24a, 24b and 24d, 24e respectively are provided liquid distributors 25, which are supplied (see particularly FIG. 4) by means of pumps 26 which draw-in through a pipe 38 the liquor which is exuded from the pulp during the course of its coagulation. It should be noted that these pumps are arranged so as to recycle only a part of the exuded liquor into the distributors 25, the remaining part being directed towards the recovery tank, whereby the level of the liquor is maintained and a circulation of this liquor is established in order to make the coagulation medium uniform. This recycling is effected by means of conduits 39 which lead from the pumps 26 and terminate at the distributors 25.

On the other side of the last pressure roller 24g is mounted the extraction station 27, clearly shown in FIG.

5, and this is followed by the transfer station 28 of the coagulated bar. The extraction station, close the feed station, is made-up of a shoe 40 placed in the mould; this shoe is oscillating and is carried by means of a frame 41 pivoted on a stud carried by the outer ring 22. This shoe, made of insulating material, has an upwardly-sloping ramp 42 followed by a flat portion 43, while cheeks 44, 45, carried by the outer ring are advantageously arranged to facilitate the transfer of the bar extracted from the mould 11 to the driving means 28.

10 These latter means comprise a first pair of guiding rollers 46 and 47 with smooth surfaces; these rollers, mounted one below the other, rotate freely on horizontal spindles 48 carried by vertical brackets 49, fixed for example on the ring 22.

15 On the other side of these guiding rollers are arranged pairs of rollers with vertical axes, some with smooth surfaces, the other driving rollers with fluted surfaces, which are arranged alternately. Two pairs of driving rollers 50 with fluted surfaces and two pairs of guiding rollers 51 with smooth surfaces are thus mounted laterally to the bar which has been formed; however, these driving means in one alternative form of construction may only comprise driving rollers with fluted surfaces.

20 25 It should be noted that the driving rollers 50 are driven at a suitable speed by means of one or more motors with speed-varying gear (not shown), the linear speed of these rollers being equal to the tangential speed of the mould.

25 Reference will now be made more particularly to FIG. 30 30 6 which shows the washing station located in the space comprised between the feed station 23 and the extraction station 27. This washing station comprises two scrapers 53, 54 which are engaged in the mould 11, spaced apart and carried on arms 55 fixed to the outer ring. These 35 scrapers are preferably of rubber and are in close contact with the inner walls 12, 13, 14 of the mould, so as to ensure the cleaning of these walls by a rubbing action. This arrangement creates a lock-chamber 56 in the mould, level with which is provided, on the one hand a distributor 57 for the washing water and on the other hand, conduits 58 coupled by piping 59 to a suction pump 60.

40 45 During the operation of the device, that is to say when the mould is rotating, the distributor 57 for washing water is continuously supplied, while the suction pump 60 is in action, so that the washing water which is in the lock-chamber is constantly renewed during the rotation, which thus provides effective cleaning of the walls of the chamber.

The operation of the device described above may be analysed in the following manner.

50 55 The mould 11 being given a rotating movement by rotation of the plate 10, the pulp P which is in particular composed of viscose, reinforcing fibres and crystals of sodium sulphate, is fed in at a constant rate of flow by the screw 30 and is distributed by the conduit 32, 33 to the interior of the mould in the vicinity of the bottom 12, so as to avoid any reflux of the pulp towards the rear.

60 It will be observed that, due to the shape given to the pipe 32, 33, the course of the pulp is subjected to two changes in direction, which produces a de-orientation of the fibres in the pulp, the latter having been considerably directed towards the upstream side by the effect of the feed-screw.

65 The pulp P moves with the mould 11 and thus follows a circular travel of limited extent from the feeding station to the extraction station. During its movement, the pulp is traversed by an electric current which is transmitted through the walls of the mould, acting as electrodes, and this causes progressive coagulation of the said pulp.

70 75 During its coagulation, the pulp shrinks and becomes detached from the walls of the mould after having effected part of its circular travel; it is at this stage that the pressing rollers 36 come into action and, by pressing on the coagulated bar, hold the latter down inside the mould and keep it immersed in the exuded coagulation liquor.

The suction pumps 26 extract the excess coagulation liquor formed from the surface; this liquor is sent in part towards the recovery tank, while the remainder is recycled and distributed by the distributors 25 over the pulp in course of coagulation. By virtue of the gutters 19 and 20 on the edge of the mould, the contacts are protected from any possible overflow of the liquor.

The bar of coagulated pulp is traversed by the electric current from the feed station up to the extraction station, at which it must arrive in the coagulated state. At this point, the bar is extracted from the mould by the shoe 40 by means of the sloping ramp 42, and then it is guided by the cheeks 44 and 45 and subsequently passes between the guiding rollers 46, 47, from which it is taken and driven by the pairs of rollers 50, 51 which lead it towards the usual washing and finishing baths.

It should be noted that the exuded liquor contained in the mould cannot penetrate into the lock-chamber 56, the scrapers 53, 54 of which are arranged to form fluid-tight joints, both on the feed side and on the extraction side.

An asynchronous motor connected to a source of three-phase current is preferably employed to supply the transformer 18 through the intermediary of an alternator and a rotating contact. As regards the mould elements 13, 14 which form the walls of this latter, they may be of any desired number; however, each wall of the mould is preferably made-up of twelve elements. In the example described, the mould section is of U-shape; it will easily be seen that the mould elements may be given an in-curved profile or any other profile which enables a desired shape of sponge to be obtained. This is obviously true also with regard to the bottom of the mould.

Furthermore, in order to prevent the production of curved blocks of sponge, the diameter of the mould will preferably be greater than 3.50 m., while the electrical supply may be obtained by transformation of three-phase current to hexaphase current, and then to single phase by means of rectifiers and a thyatron inverter.

In an alternative form of embodiment, the device may be of the multiple type. It may for example comprise a number of concentric moulds mounted on a single plate. Similarly, a number of plates provided with one or a number of moulds may be superimposed on a common vertical driving shaft, each of the moulds, three for example, being connected to one phase of a three-phase current supply.

The device is advantageously surmounted by a canopy for drawing-out the gases.

Also in an alternative form, the evacuation of the liquors may be effected by suction, and the circulation of these liquors may be effected by means other than the pumps referred to, for example by means of bucket elevators.

It will of course be understood that the invention is not limited to the forms of construction described, which may on the contrary form the subject of modifications, without thereby departing from the scope of the invention.

What I claim is:

1. A device for the continuous manufacture of artificial sponges, including at least one horizontal plate mounted for rotational movement, said plate being provided with at least one annular mould open at its upper part, said mould being coupled to a source of electric current to assist in coagulation of pulp in said mould, a plurality of fixed stations including means for feeding pulp to said mould, means for pressing pulp in said mould, means for extracting from said mould liquid exuded during coagulation of pulp in said mould, means for removing pulp from said mould including driving means external to said plate, means located between said removing means and said feeding means for washing said mould, said mould passing with rotations of said plate in front of said plurality of fixed stations.

2. A device as claimed in claim 1, in which said mould proper has a straight transverse section of U-shape.

3. A device as claimed in claim 1, in which the mould includes vertical walls constituted by a plurality of metal elements end-to-end, said elements being coupled together by fluid-tight and insulating expansion joints, and the bottom of said mould including a ring of insulating material.

4. A device as claimed in claim 3, in which each of the walls of said mould is constituted by twelve elements.

5. A device as claimed in claim 1, in which the mould includes upstanding walls, the upper part of the walls including gutters arranged to evacuate any overflow of liquid from the mould to a recovery tank.

6. A device as claimed in claim 1, in which said pulp-feeding means includes an endless screw rotatably mounted in a tube, said tube being extended, beyond said screw, by a section elbowed first substantially through 90° downwards and secondly substantially at 90° in the direction of rotation of said plate and said mould.

7. A device as claimed in claim 1, in which said pressing means are constituted by rollers adapted to rotate freely, said rollers being vertically displaceable in slides formed in a supporting arm, said arm being rigidly fixed to a fixed support station adjacent the edge of said plate.

8. A device as claimed in claim 1, in which said means for extracting from the mould the liquor exuded during the course of coagulation comprise at least one suction pump provided with branches to re-cycle part of the extracted liquid and directed part of said liquid to a recovery tank.

9. A device as claimed in claim 1, in which, beyond said removing means, means are provided to receive the bar of coagulated material including guiding rollers having horizontal axes, vertically mounted rollers driven in rotation and disposed laterally to said bar, at least some of said rollers being provided with fluted surfaces.

10. A device as claimed in claim 1, constituted by a plurality of superposed plates, each said plate comprising a plurality of concentric moulds.

11. A device as claimed in claim 1 wherein said washing means includes arcuately spaced scrapers forming a lock in said mould and means for pumping liquid into and removing liquid from said lock.

12. A device for the continuous production of artificial sponge including:

- (a) a rotably mounted annular mould,
- (b) a stationarily mounted pulp feeding unit positioned adjacent said mould,
- (c) at least one stationarily mounted pulp pressing unit positioned to overlie said mould, and
- (d) means stationarily mounted adjacent said mould for removing pulp from the mould upon rotation of said mould through an arc of approximately 270°.

13. A device as defined in claim 12 further including means connected to said mould and passing an electrical current through pulp in said mould.

14. A device as defined in claim 12 wherein said mould is horizontally positioned for rotation about a vertical axis, the mould being coaxial with the axes of rotation, the mould having an open upper surface through which pulp may be fed from the feeding means and removed by the removing means after said mould is rotated through an arc of approximately 270°.

15. A device as defined in claim 14 wherein the pulp pressing unit includes a roller having an axis parallel to the radius of the annular mould and mounted for free rotation and vertical movement.

16. A device as defined in claim 14 further including liquid removing means positioned adjacent the open portion of the annular mould for removing liquid from said mould and recycling a portion of the liquid back to the mould and a portion of the liquid to a recovery tank.

17. A device as defined in claim 14 wherein said annular mould is horizontally mounted coaxial with its vertical axes of rotation and having an open upper

surface with troughs adjacent each side of the upper surface to receive any overflow from said mould.

18. A device according to claim 17 wherein electrodes are connected to said mould to transmit an electrical current through any pulp positioned within the mould.
